UNITED STATES PATENT OFFICE.

LEONARD LE BARON AND ARTHUR C. HARRELL, OF PENSACOLA, FLORIDA.

AUTOMATIC TRAIN-PIPE COUPLING.

1,407,665.

Specification of Letters Patent. Patented Feb. 21, 1922.

Application filed January 5, 1921. Serial No. 435,195.

To all whom it may concern:

Be it known that we, LEONARD LE BARON and ARTHUR C. HARRELL, citizens of the United States, both residing at Pensacola, 5 county of Escambia, and State of Florida, have invented certain new and useful Improvements in Automatic Train-Pipe Couplings; and we do hereby declare the following to be a full, clear, and exact description 10 of the invention, such as will enable others skilled in the art to which it appertains to make and use the same.

The present invention relates to improvements in automatic train pipe couplings and 15 resides more particularly in an improved locking device whereby the coupling parts are held in a proper position and against accidental rotation until they are brought together relatively so that the proper coupling 20 may be had when the coupling heads are rotated in opposite directions.

Great difficulty has been experienced heretofore in the coupling of cars of different heights because the rotary coupling heads 25 will be accidentally shifted which causes the co-operating pins and hooks to strike one another and prevent their inter-engagement when the coupling heads are rotated and, in fact, prevent the proper coming together of 30 the coupling heads.

The above difficulty is removed by the present locking device which holds the rotary coupling heads in an initial position and against accidental rotation until the 35 hooks and pins are moved to an overlapping position such that their inter-engagement will be insured when the coupling heads are rotated.

It is another object of the invention to 40 carry out the above described purposes by a simple and effective construction which is automatic in action.

With the foregoing and other objects in view, the invention will be more fully described in connection with the accompanying drawings wherein like symbols refer to like or corresponding parts throughout the several views, and wherein:

Fig. 1 is a fragmentary view of a pair of 45 train pipes on adjoining cars together with an improved coupling constructed in accord-

ance with the present invention and shown in the closed position;

Fig. 2 is a transverse sectional view taken on the line 2—2 in Fig. 1; 55

Fig. 3 is an enlarged fragmentary view of the two pipes with the coupling heads shown partially in elevation and partially in section;

Fig. 4 is a cross-sectional view taken on 60 the line 4—4 in Fig. 3;

Fig. 5 is an enlarged fragmentary sectional view through a portion of the locking device;

Fig. 6 is a fragmentary partial elevation 65 and sectional view showing the locking device in normal position, and

Fig. 7 is a similar view showing the locking device in the unlocked position.

Referring more particularly to the drawings, 1 and 2 designate adjoining train pipes on two cars to be coupled. These cars are equipped with cuffs 3 and sleeves 4 as constructed in accordance with the invention contained in my prior co-pending application Serial No. 339,673, filed November 21, 1919. According to this invention the cuffs 3 are provided with slots 5 having flaring mouths 6 at their outer ends and communicating with offset slots 7 in the sleeves 4. The 80 sleeves 4 are semi-cylindrical in construction as are likewise the cuffs in order to enable the cuffs and sleeves on one car to pass those of the other. 75

As shown more particularly in Fig. 3 the 85 pipes 1 and 2 are provided with fixed heads 8 and 9 respectively having sockets 10 to receive cylindrical or other shaped plungers 11 provided with reduced pins 12 on their inner ends about which are coiled springs 13 acting to normally project the plungers 11 into semi-cylindrical depressions 14 made in rotary heads 15 and 16. These rotary heads 15 and 16 are mounted respectively on the two train pipes in conjunction with the 95 heads 8 and 9.

One form of connection with the rotary heads is shown in Fig. 3 in which the head is internally screwthreaded to receive an externally threaded ring 17 having a flange 18 100 projecting inwardly at one side for engagement against a second rim 19 threaded in-

ternally to screw onto the externally threaded end of the train pipe.

In this way the head 15 is permitted to rotate while it is prevented from escaping by the contact of the shoulder 18 against the smaller ring 19. Compressible gaskets 20 and 21 are carried by the heads 15 and 16 and are adapted to be engaged when the heads are in coupled position.

10 The head 15 carries a hook 22 at one side projecting outwardly therefrom and adapted to engage about a pin 23 on the opposite rotary head 16 when the two heads are rotated partially in opposite directions. In a similar manner a hook 24 on the rotary head 16 extends at a diametrical opposite point from the pin 23 and is adapted to engage with the second pin 25 projecting from the companion rotary head 15 diametrically opposite to the hook 22.

Ball bearing rollers 26 and 27 are carried by the pins 23 and 25 for anti-frictionally engaging the walls of the slots 5 and 7 in the cuffs 3 and sleeves 4 respectively. The hooks 22 and 24 are so disposed as to strike projections 28 on the outer half portions of the plungers 11 so that said plungers may be shifted thereby out of the depressions 14.

In use, the plungers 11 normally occupy the depressions 14 and prevent any accidental rotation of the rotary heads 15 and 16. In this locked position the hooks 22 and 24 are in alignment with the projections 28 of the plungers 11. As the two cars are brought together, the hooks will advance in rectilinear paths as indicated in Figs. 6 and 7 and before any rotation of the heads can occur, such hooks must strike the projections 28 and shift the plungers into the socket 10 and out of the depressions 14 as appears in Fig. 7.

This is arranged to take place while the rollers 26 and 27 on the pins are in the slots 5 of the cuffs 3 and before they enter the offset slots 7 in the sleeves 4. The rotary heads 15 will thus be free to rotate as soon as the rollers on the pins start into the offset slots 7 which will cause the swinging of the rollers and pins and consequently a partial rotation of the heads is such as will interlock the hooks with the inner portions of said pins. When the cars are uncoupled, the reverse will take place, the heads being first rotated so as to bring the plungers into alignment with the depressions so that the rotary heads 15 will be locked as the cars move away from each other.

We have described preferred and satisfactory construction and obviously changes may be made without departing from the spirit of the invention provided such changes are within the scope of the appended claims.

What is claimed is:

1. In combination with adjacent train pipes, rotatable heads carried by said train pipes and adapted to be brought together

when in coupled position, means for engaging said heads in coupled position, and means released by said last named means for normally preventing the rotation of said heads, substantially as described.

2. In combination with adjoining train pipes, rotatable heads thereon, means for normally holding said heads against rotation, and coupling means for the heads adapted to be engaged by a turning movement of said heads, said coupling means adapted to initially engage the means for holding said heads against rotation and for disengaging the same, substantially as described.

3. In combination with a pair of train pipes carried by adjacent cars, rotatable heads on said train pipes, plungers for normally holding said heads against rotation, and coupling means for the heads adapted to be engaged by rotary movement of the heads in opposite directions, said coupling means adapted to initially engage said plungers whereby to release the heads, substantially as described.

4. In combination with two train pipes, rotatable heads carried thereby having sockets therein, plungers carried by the pipes and adapted to enter said sockets to normally hold the heads against rotation, and inter-engaging coupling means carried by the adjacent heads adapted to be engaged by movement of the heads in opposite directions, portions of said coupling means adapted to strike said plungers initially and move the same out of said sockets, substantially as described.

5. In combination with adjacent train pipes, rotatable heads carried thereby and provided with sockets, plungers carried by the train pipes adjacent the heads and yieldingly urged into said sockets whereby to avoid rotation of said heads, co-operating pins and hooks carried by said heads and adapted to be engaged by rotary movement of the heads in opposite directions, said hooks lying in the path of the plungers and adapted to remove the same from said sockets, substantially as described.

6. In combination with a pair of train pipes, fixed heads thereon, rotatable heads mounted in conjunction with said fixed heads, means carried by the fixed heads to normally prevent the rotation of said rotatable heads, and coupling means adapted to unite the rotatable heads and initially acting on said last named means to free the rotatable heads, substantially as described.

7. In combination with a pair of train pipes, fixed heads carried thereby, yieldably mounted plungers in said fixed heads, rotary heads mounted in conjunction with said fixed heads and having sockets normally engaged by the ends of said plungers, and coupling means between the rotatable heads adapted to

to initially engage said plungers and shift the same out of said sockets, substantially as described.

8. In combination with adjacent train pipes, a pair of fixed heads carried thereby, a pair of rotatable heads mounted in conjunction with said fixed heads and adapted to be brought together, compressible gaskets meeting between said rotatable heads, means carried by the fixed heads and normally and yieldingly engaging with the rotatable heads to hold the latter against rotation, and pin and hook coupling connections carried by said rotary heads and adapted to be inter-engaged by a partial rotary movement of the 15 heads in opposite directions, said hooks lying in the path of said means and adapted to initially free the rotary heads, substantially as described.

LEONARD LE BARON.
ARTHUR C. HARRELL.
